UNITED STATES PATENT OFFICE.

HERBERT AUGUSTUS BULLARD, OF SAN FRANCISCO, CALIFORNIA.

SAFETY-RAZOR.

No. 851,341.

Specification of Letters Patent.

Patented April 23, 1907.

Application filed September 18, 1905. Serial No. 278,916.

To all whom it may concern:

Be it known that I, HERBERT AUGUSTUS BULLARD, a citizen of the United States, and a resident of the city and county of San Francisco, State of California, have invented 5 certain new and useful Improvements in Safety-Razors, of which the following is a specification.

My invention relates to safety razors, and 10 has for its object to provide a razor of this class, of improved construction, simple, and economical.

I attain my object by the means illustrated 15 in the accompanying drawings, of which

Figure 1 is a side view of my razor, Fig. 2 is a vertical transverse section of my razor with the blade attached, and Fig. 3 a top view. Fig. 4 is a view of my razor blade, and Fig. 5 is a vertical transverse sectional view of my 20 holder with the blade removed.

Similar numerals of reference refer to similar parts throughout the several views, which are all on an enlarged scale.

My invention consists in a general way of 25 the improved holder, the improved blade, and the improved means of securing the blade to the holder.

More particularly, and describing the holder 1, first, it consists of a sheet of spring 30 metal stamped and shaped into substantially the form shown in the drawing. The guards 2, 3, usually provided in safety razors, are stamped out of the sheet along on lines somewhat near the extremities thereof.

The sheet is folded at its center into two 35 sides, and formed into angles along the aforesaid lines, the tops of said angles forming blade supports, and the ends turned outwardly to form part of the blade securing

means 4, 5. The other part of the blade securing means is on the blade itself, and consists of the longer sides of an oblong aperture 40 7 in said blade. The spring of the metal of said holder is so set as to tend to throw the

parts 4 and 5 away from each other, and to cause the aforesaid sides to spring outwardly against the said longer sides. Said sides are made of such size as to fit the sides supporting 4 and 5 snugly. The aperture 7 is made

of such size as to admit the passage of the parts 4, 5 when they are pinched together. When they are released they spring outwardly to engage the blade, and secure it 45 against the guards 2, 3.

Blade 6 consists of a sheet of metal having 55 opposite cutting edges. It is provided with an oblong aperture 7, the center of which is nearer to one cutting surface than the other, whereby one cutting edge is caused to lie closer to the edge of its guard, than the other 60 cutting edge lies to its corresponding guard, and thus enables the user to shave closely or not as he desires.

The holder is by the described construction a spring-box having open ends and two 65 outwardly tending flat springs carrying guards and having a part supporting the blade and having its extremities bent outwardly. The outward pressure of the aforesaid flat springs is received by the longer 70 sides of the aforesaid oblong aperture of the blade, and the outwardly bent portions 4, 5 act to secure said blade against the guard portion 2, 3, in co-operation with said longer sides.

Having described my invention what I claim as new and desire to secure by Letters Patent of the United States is—

1. A holder for safety razor blade, comprising a sheet of spring metal shaped to form 80 two outwardly-pressing flat spring members joined at one end to form a finger and thumb hold, said members intermediate their ends bent to form an angular ridge constituting a blade support, guards formed along the 85 apex of each angular ridge, the upper extremities of said spring members curved outwardly and downwardly in opposite directions to each other and constituting blade-securing means.

2. A blade for safety razors comprising a rectangular body having opposite side cutting edges and provided with an oblong aperture, the center of which is nearer one cutting edge than the other and one of which cutting 95 edges is of greater width than the other cutting edge.

3. A safety razor blade comprising a body having opposite cutting edges and provided with an oblong aperture, the center of which 100 is nearer one cutting edge than the other and nearer to one end of the body than to the other.

4. In a safety razor a blade having opposite cutting edges and an oblong aperture the 105 center of which is nearer one cutting edge than the other.

5. A safety razor comprising a holder

shaped out of a sheet of spring metal into two outwardly pressing flat springs joined at one end to form a finger and thumb hold, and provided with guards, blade supports and 5 blade-securing means at the other end, in combination with a blade having opposite cutting edges and an oblong aperture the center of which is nearer one edge than the

other, and the longer sides whereof are adapted to snugly engage said springs. ¹⁰

In testimony whereof I hereunto sign my name in the presence of two witnesses.

HERBERT AUGUSTUS BULLARD.
